FOREIGN PATENT DOCUMENTS

JP D1452648 * 10/2012

Primary Examiner — John R Yeh(74) *Attorney, Agent, or Firm* — Rumit Ranjit Kanakia(57) **CLAIM**

The ornamental design for a phone case stand, as shown and described.

DESCRIPTION

FIG. 1 is a perspective view of a phone case stand showing my new design in an environment of use.

FIG. 2 is a second perspective view without environment thereof;

FIG. 3 is the second perspective view thereof;

FIG. 4 is the third perspective view thereof;

FIG. 5 is a front elevational view;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is the perspective view showing that the phone case stand is in a closed status;

FIG. 12 is a partial enlarged view of FIG. 2;

FIG. 13 is a partial enlarged view of FIG. 3; and,

FIG. 14 is a partial enlarged view of FIG. 4.

The broken lines depict enlargement indications and environment of the phone case stand that form no part of the claimed design.

1 Claim, 14 Drawing Sheets**FIG.12**(56)
